TYPE FORM MAKE-UP DEVICE

Clarence L. Self, Austin, Minn., assignor to V. B. McGuire Manufacturing Company, Northfield, Minn., a partnership composed of Clarence L. Self and V. B. McGuire

Application December 28, 1936, Serial No. 117,685

31 Claims. (Cl. 276—43)

This invention relates to devices for use in making up type form pages and further relates to devices for clamping together the made up type form pages.

5 In accordance with general practice in the printing art, "Monotype" or "Linotype" are set up by hand into forms representing a page or smaller unit on a working surface known in the trade as a galley. These galleys, which are in the nature 10 of a flat rectangular surface, are provided at certain of their adjoining edges with upturned flanges, against which upturned adjoining edges the type is built up into a longitudinally straight-sided type form page. The operator, known in 15 the trade as the "make up man", builds the type group up to approximately desired page length and then, by compressing the group longitudinally by hand and measuring with a rule, determines the error in exact length at opposite 20 sides of the group, such error usually being due to error in thickness of the individual type of the group, and then by insertion and/or removal of filler shims brings the type group to what he determines is the desired overall length and 25 squareness, and then ties the group up with twine or the like to be passed on and locked up with other type groups or forms for the printing operation. This system of manually compressing and measuring for length and true ness with a 30 rule is not only slow and tedious, but is not apt to be highly accurate, due to the fact that the compressibility of the complete unit is partially taken up by hand pressure which is not uniform and which often is not uniformly applied to opposite 35 sides of the form. The result of such measuring of a type form for squareness and length under varying degrees of a poorly distributed pressure is that when the type forms thus made up are later passed through the lock-up process, where- 40 in they are subject to a relatively greater pressure and for which purpose they must be of true length and squareness, the lock-up operator is required to waste much time and energy in finishing the job of truing up the type form for 45 length and squareness by further removal and/or insertion of shims between type rows.

The present invention provides, in combination with a galley of improved form, a tool or device by means of which a built-up type form page 50 may be quickly and easily subjected to equalized longitudinally exerted pressure for the purpose of measuring up for length and true ness, and in its preferred form includes an automatically operated meter for indicating the length and squareness of the built-up type page form, while sub-

ject to equalized pressure. In the preferred embodiment of the invention this pressure producing and indicating apparatus is adjustably slideable longitudinally of the galleys and is readily shifted from inoperative position, wherein it in no way interferes with the building up of the type page form, to an operative position, wherein it is used to compress the type page form and check the length and true ness thereof, and wherein it also serves as a means for compressing the type 10 and holding the same compressed while it is tied or clamped up.

Several important objects of the invention will be made apparent from the above and others thereof will be made apparent from the following specification and claims and the attached 15 accompanying drawings, wherein like characters indicate like parts throughout the several views.

Referring to the drawings:

Fig. 1 is a plan view of the complete apparatus having a two-column type form page built up and in operative position on the working surface of the galley;

Fig. 2 is a plan view similar to Fig. 1 and with its several parts positioned as in Fig. 1 but having certain parts thereof broken away and certain thereof shown in section, further illustrating the details of the mechanism;

Fig. 3 is a view broken away in section in accordance with Fig. 2, but showing the pressure 30 producing and indicating mechanism shifted to an operative position;

Fig. 4 is a detail sectional view taken on the line 4—4 of Fig. 1;

Fig. 5 is a detail sectional view taken on the 35 line 5—5 of Fig. 1, some parts on the section line being omitted;

Fig. 6 is a detail sectional view with some parts shown in full, taken on the line 6—6 of Fig. 1;

Fig. 7 is a detail sectional view taken on the 40 line 7—7 of Fig. 6;

Fig. 8 is an enlarged fragmentary view in perspective illustrating a step in the process of applying the tie-up devices to a type page form; and

Fig. 9 is an enlarged fragmentary view in end elevation of a type page form tied up by means of the improved clamping devices.

The galley, indicated as an entirety by 10, is in the nature of a rectangular tray having a flat 50 bottom working surface 11 and upstanding rails at its front end and two sides and being open at its rear end. The front upstanding rail of the galley is indicated by 12, the right-hand upstanding rail of the galley is indicated by 13, and the 55

left-hand upstanding rail is indicated by 14. The front upstanding rail is undercut to provide an overhanging horizontal flange 15 and an underlying groove 16. The left-hand upstanding rail 5 of the galley, indicated by 14, is provided at its horizontal upper edge with an inwardly projecting flange 17 that projects over and inwardly of the rail 14 in parallel relation thereto and is removably but securely anchored thereto by screws 10 18. Applied to the upper surface of this inwardly projecting flange 17 is a printer's scale 19 calibrated in half-pica measurements. The pressure producing and indicating apparatus is all carried by a sliding casing-acting frame 20 that 15 is slidable on the flat bottom 11 of the galley and is guided for true longitudinal sliding movements by the longitudinal side rail 14 of the galley, to which said frame is slidably interlocked. In this respect it will be seen, by examination particularly of Fig. 5, that the upstanding front rail of the frame 20 projects under the inwardly projecting flange 17 of the galley side rail 14; and by reference particularly to Figs. 1 and 5, it will be seen that the frame 20 is equipped with a cover 20 plate 21 that is removably applied thereto by means of screws or the like 22, and is, at its left-hand edge portion, formed to afford a down turned flange 23 that works against the outside longitudinal surface of the galley rail 14, thus 25 removably interlocking the frame 20 to the galley rail 14 for longitudinal sliding action and preventing removal thereof except by extreme longitudinal sliding action rearwardly beyond the end of the flange 17 of the galley rail 14, which flange, 30 it will be noted, terminates considerably forward of the rear end of the galley but is, nevertheless, of sufficient length to maintain suitable interlocking engagement between the frame 20 and the galley rail 14 throughout all of the operative positions of said frame 20. The front edge of the frame 20 extends in a plane exactly parallel to the front rail 12 of the galley and therefore intersects the plane of the galley side rail 14 at exactly 40 a 90° angle.

45 Located directly forward of and extending in parallel relation to the front edge of the frame 20 is an extensible and retractable primary rail 24 that is carried by the frame 20 through the medium of push rods 25. These push rods 25 are 50 securely and rigidly anchored to the rail 20 and work slidably through suitable apertures in the front and rear walls of the frame 20. Preferably the left-hand end of the primary rail 24 will slidably engage the inside edge of the galley rail 14 55 substantially as shown in the drawings. The push rods 25 are normally retracted to a position, wherein the primary rail 24 is against the front edge of the frame 20, by suitable compression springs 25' applied over the push rods and 60 confined between the front edge of the frame 20 and suitable collars 26 on said push rods.

The mechanism herein illustrated for extending the push rods and primary rail 24 against the action of said springs 25' compresses an operating handle 27 that is mounted fast on a vertically extended operating shaft 28, journaled in the frame 20, and its cover plate 21, bell cranks 29, links 30 and a crank disc 31. The handle 27 is made fast on the shaft or spindle 28 by means 65 of a suitable pin or the like 32 which permits removal of the handle. The crank-acting disc 31 may be made fast on the shaft by any suitable means such as a pin 33 and is formed at its periphery to afford suitable spaced stops 34 and 70 35 which cooperate with a spring 36 to resiliently

retain the crank disc in either of its extreme positions. The bell cranks 29 are pivotally anchored to the frame 20 at 37, and the links 30 are each pivoted at one end to a bell crank 29 and at its other end to a diametrically opposite point on the 5 crank disc 31. The free outer ends of the bell cranks 29 work against the rear faces of the collars 26 so that under rotation of the handle and consequent rotation of the crank disc 31, the push rods 25 and rail 24 may be projected from 10 the position shown in Figs. 1 and 2 to the position shown in Fig. 3, in which latter position, it will be noted, the links 30 are in their dead center positions, wherein they are substantially capable of resisting retracting pressure of the 15 springs 25 unaided. However, such tendency as may exist to automatically return the extended parts to their retracted position under the action of the springs 25 will further be resisted by the spring 36, which now resiliently engages the stop 20 34.

Longitudinally slidably interlocked to the front longitudinal edge of the extensible and retractable rail 24 by interlocking flange and channel engagement at 38, see particularly Fig. 6, is a 25 bar 39, which bar 39 carries, through the medium of a stud pin 40, a similar bar 41. The stud pin 40 is screw-threaded into the bar 41 and works in the bar 39 for free axial sliding movements and for free rocking movements in the plane of the bottom 11 of the galley. The bar 41 is normally spaced from the bar 39, as shown in Figs. 1, 2 and 7 for example, and is limited against further movement away from the bar 39 by engagement of the head 42 of the stud pin 40 with a shoulder 30 formed by reducing the pin-receiving bore through the bar 39 to provide a relatively narrow guide collar 43 for the pin 40. There is enough clearance between the collar 43 and the pin 40 to permit the above described rocking action of the 40 bar 41 in respect to the bar 39, and, of course, there also must be sufficient clearance between the head 42 of the pin and the sides of the enlarged portion of the bore to permit of such rocking action.

45 Interposed between the bars 39 and 41 near opposite sides thereof and at points equally spaced from the stud pin 40 is a pair of like compression springs 44 that maintain the bars 39 and 41 normally spaced apart the maximum distance permitted by the head 42 of the stud pin. These springs 44 are seated at their opposite ends in opposed socket-forming recesses in the opposed bars 39 and 41. To prevent vertical wobbling of the bar 39 and any tendency of said bar 41 to 50 rotate on its axis, the bar 39 is provided at its opposite ends with rearwardly extended guide tongues 45 that work slidably in slots or grooves 46 in the bar 41. As will be seen, particularly by reference to Fig. 7, there is sufficient clearance 55 between the tongues 45 and the bottom of the grooves 46 to permit the desired free wobbling or oscillating action of the bar 41 with respect to the bar 39 in the direction of a plane of the base of the galley about the axis formed by engagement of the stud pin 40 with the shoulder 43 of the bar 39.

Slidably interlocked to the front side of the bar 41 by flange and channel engagement in the same manner as the bar 39 is slidably engaged 70 by primary rail 24, is a secondary rail 47. This secondary rail 47 slidably engages the galley rail 14 and is preferably rounded at its galley-rail-engaging end to permit free pivot oscillation thereof with the bar 41. At their outer or right- 75

hand ends the primary and secondary rails 24 and 41 are tied together for limited movements longitudinally of the galley and for limited oscillatory movements of the type described by a pair of overlapping links 48 and 49, the former of which is provided with screws or the like 50 that work loosely in slot 51 in the latter link. These screw-threaded and slot-equipped links 48 and 49 prevent lateral shifting of the secondary rail 47 with respect to the primary rail 24 and prevent accidental displacement of the bars 41 and 39 by longitudinal sliding action, but it is important to note that there is sufficient clearance between the heads of the screws 50 and the outer surface of the link 49 to permit the desired oscillatory action of the secondary rail 47 and its immediately associated bar 41.

The primary and secondary rails 24 and 47 may hereinafter be respectively referred to as primary 20 and secondary pressure rails; and the bars 39 and 41, since together they form a cross-head, may hereinafter be referred to collectively as a split crosshead, and singularly as the sections of a crosshead.

25 For adjustably limiting forward movements of the carriage-acting frame 20 there is provided an adjustable stop device 52. This stop device 52 has longitudinal sliding lateral interlocking engagement with the galley rail 14, and is provided 30 with a spring pressed manually retractable stop pin 53 that is projectable into any one of a long series of pin-receiving apertures 54 in the galley rail 14. The said longitudinal sliding lateral interlocking engagement between the stop device 52 and galley rail 14 is afforded by engagement of an L-shaped keeper lug 55 that works slidably in an L-shaped grooveway 56 extending longitudinally of the galley rail 14 and formed partially therein and completed by the rigidly but removably secured horizontal flange 17 thereof. The stop device 52 is engaged by the down-turned portion of the carriage frame cover plate 21 to limit forward movements of the latter and is provided at its upper surface with an inwardly projecting pointer 57 that works over the surface of the scale 19 and co-operates with said scale to indicate the proper position for setting the stop for any desired type-form-page length. Since the scale 19 is calibrated in pica measurements, the stop pin-receiving apertures in the galley rail 14 are spaced one pica apart. In use the sliding stop device 52 is adjusted vertically with the stop pin retracted until the pointer 57 is opposite the scale calibration, indicating the 55 desired type-page length and then is locked in that position by releasing the stop pin 53 and permitting the same to project into an alined aperture in the galley rail 14. For purposes hereinafter made clear, the stop device 52 is provided 60 with a spring retracted push pin 58 that is so positioned with respect to the lock pin 53 that it will always be alined with one of the galley rail apertures 54 when the stop pin is operatively engaged with another thereof. This push pin 58 65 works in a guide sleeve 59 and is provided with a projecting finger piece 60 that works through a slot 61 in the guide sleeve. Retracting movements of the push pin under action of its spring are limited by a suitable projection 62.

70 As will hereinafter be made clear, the bars 39 and 41 together with their co-operating springs 44, besides serving as a means for applying yielding pressure to a set-up type form, serve also as part of a laterally shiftable indicating device, 75 by means of which the trueness or error in over-

all type form length and squareness may be readily detected by the operator. To complete this indicator a dial plate 63 is secured to the bar 39 by screws or the like 64 and slidably overlaps the upper face of the bar 41; and co-operating with horizontal calibrations on this dial plate are opposed like pointers 65, each of which are pivoted at their ends to an opposite end portion of the bar 39 at 66, and each of which pointers 65 is intermediately pivotally connected by means 10 of a link 67 to the bar 41.

In order to positively lock the carriage-acting frame and certain of its associated parts, in a desired position determined by engagement thereof with the stop dog, for operations of compressing 15 and measuring a type form group or page, there is provided an automatic lock mechanism 68 which is moved into operative position automatically by initial projecting movements of the primary rail 24 through manipulation of the handle 27 20 and its associated linkage including the bell cranks 29, and which lock is automatically released under final retracting movements of said rail 24. This automatic lock mechanism 68 consists of pivoted latch arm 69 carrying at its free end, pins 70 for 25 engagement with apertures 54 of the galley rail 14, a slide 71 that is operatively coupled to and moved with one of the push rods 25, and a link 72 operatively coupling the latch arm 69 and slide 71. The latch arm 69 is pivotally anchored to the 30 bottom of the carriage-acting frame 20 at 73 and is provided near its free end with a cam surface 74 that is engaged by a rounded type end of the slide 71 to move the lock pins 70 into operative engagement with the perforations in the galley 35 rail 14. The slide 71 is held against lateral movements and guided for true longitudinal sliding movements by projecting stops 75 and 76, and its operative engagement with the adjacent push rods 25 is affected by engagement of spaced lugs 77 40 and 78 on said slide with opposite sides of the collar 26 of said adjacent push rods. It will be obvious that under projecting movements of push rods 25 and primary rail 24 that the slide 71 will ride over the cam surface 74 of the latch arm and 45 cause projection of the latch pins 70 into alined apertures 54, thereby locking the carriage-acting frame against sliding movement. By reference now to Figs. 2 and 3 it will be seen that the link 72 is pivotally anchored to the latch arm 69 and 50 is loosely coupled to the slide 71 by slot and pin connection at 79 so that under final retracting movements of the slide, the link 72 will be brought into action to withdraw the latch arm and its pins 70 from a locked position to a normal or inoperative position.

As a means for automatically taking up any slack which may exist between the galley rail 14 and the engaged carriage-acting frame 20 and its cover plate 21 and thereby positively maintaining the said carriage-acting frame 20 and primary rail 24 against wobbling action and in predetermined square, with respect to the galley under pressure, the slide 71 is provided with a rearwardly extending portion 80 that works slidably through the rear flange of the carriage frame 20 and against the inner face of the galley rail 14, and which is provided with a wedge-acting cam surface 81 for co-operating with the similarly shaped cam surface 82 on the rear flange of the 65 frame 20. Under extension of the push rods 25, primary rail 24 and slide 71, the wedge-acting cam surface 81 is brought into tight wedging engagement with its co-operating cam surface 82, and this wedge-acting engagement takes up any 70 75

slack which may exist, and a certain amount of which slack is essential in order to permit free sliding action of the carriage-acting frame, and holds the carriage-acting frame against twisting action when put under pressure.

As previously indicated, this invention further provides novel devices for tying up built and trued-up type page forms in a transportable unit, and these devices are in the nature of spring clips 83 which may be applied directly to the type or used in connection with co-operating Monotype slugs 84, as conditions or results may demand. The spring clips 83 are preferably formed from flat bands of spring steel and are provided at opposite ends with inturned, preferably reversely curved tongues 85. The spring clips 83 will be made up in various different lengths for use in connection with type page forms of different lengths, and the tongues 85 thereof may be forced over the outer edges of opposite ends of a type form page, being applied directly to the end type so as to keep the assembled type tightly pressed together, or, if the type page form is made up of Monotype or a plurality of columns of Linotype, then the Monotype slugs, cut to lengths equaling that of the type page form, will be applied across opposite ends of the type page form, and the tongues 85 of the retaining clips applied to the ends of the Monotype slugs. The Monotype slugs, as is well known, are provided with longitudinal channels 86. The tongues 85 of the spring clips are preferably reduced in width by equal or slightly less than the width of the bottom of these Monotype grooves or channels 86, and the tongues 85 are preferably applied in the grooves of the Monotype slugs, as illustrated in the drawings. In this connection it is important to note that the channels in the Monotype slugs are of greater depth than that of the reversely curved spring clip tongues.

In the absence of the above described special galley and tool combination, these clips may be advantageously employed to quickly tie-up type page forms built and measured up in accordance with the old practice, in which case the type would be compressed by hand while the spring clips were snapped over the ends of the form, but, as will hereinafter be seen, these clip devices are very advantageously used in connection with the heretofore described galley and tool.

The type form pages illustrated in the drawings each comprise two longitudinally extended columns of Linotype, each type row or line being indicated by 87 and are bound together by Monotype slugs 84 applied across the ends of the double column of type and maintained under tension to compress the type therebetween by means of a pair of the spring retaining clips 83. This manner of tying up the type page forms is not only much faster than is tying up with twine, as is conventional practice today, but has the further advantage that the clips and slugs need not be removed for the lock-up process and printing operations but may be left applied to the type during these operations so that they may be removed from the printing-press frame later and stored away in a unit without requiring untying at the time that they are locked up and retying after the printing operation. Due to the normal clearance existing between the ends of the clips 83 and the extreme outer surfaces of the Monotype slugs, the type page forms thus bound up can be subjected to substantially any degree of longitudinal pressure in the lock-up process without causing or tending to cause

buckling of the spring clips. Of course, if the spring clips are to be passed through the lock-up printing process, the lock-up operator must know and make allowance for the thickness of the spring clips, which will be a definite known 5 measurement.

For use of the improved galley and co-operating tool, in connection with the spring tie clips, the forward end portion of the galley rail 14 is provided with a tapered surface 88 that terminates 10 at the innermost edge of the galley rail 12. At the point of junction of this tapering portion of the galley rail 14 with the galley rail 12, the galley rail 14 is of a thickness just enough less than the width of the galley rail flange 17 to allow 15 for the thickness of a spring clip 83 being interposed between the thickest portion of said galley rail and the type lined up against the inner edge of the flange 17. Applied in the channel of the galley rail 12, normally having its free end 20 pressed against the end of the tapered portion 88 of the galley rail 14, is a leaf spring 89 that is securely anchored to the galley rail 12 by a rivet 90.

Operation

25

The operation of the entire apparatus, including the spring clips, will now be described.

If it is desired, as in accordance with the present example, to build up a type form page 30 consisting of two columns of Linotype, a Monotype slug 84 is first placed in the lower left-hand corner of the galley with its channeled side against the galley rail 12 and its left-hand edge against the flange 17 of the galley rail 12, with 35 a spring clip 83 positioned as, for example, in Figs. 2 or 3, wherein the main body of the clip underlies the flange 17 and the tongue thereof, at its forward end, is interposed in the channel 86 of the applied Monotype slug 84. In this position the spring 89 maintains the forward tongue of the spring clip 83 in engagement with the base of the Monotype slug channel.

During the process of building up the type page form to its approximate dimensions, the 45 carriage-acting frame and its associated parts, which are carried thereby, are slid back toward the rear of the galley where they are entirely out of the way. However, before starting the make-up process, the adjustable stop 52 will be 50 set so that its pointer 57 registers with the calibration of scale 19 indicating the desired page length plus the thickness of the Monotype slugs 84 when such are used. Hence, if it is desired to build up a type form page which is 29 picas in 55 length, the pointer 57 should be set at 31 pica calibration so as to allow for the thickness of two Monotype slugs, each of which have a thickness of one pica.

With one Monotype slug and clip 83 positioned 60 as above described, the column or columns of type are built up to the approximate desired page length, and then a Monotype slug 84 is applied across the rear end of the type form page, as indicated in the drawings. The column of type 65 adjacent the flange 17 of the galley is built up in contact with the inner edge of said flange, and the light pressure exerted by the lower type of column against the lower inner end portion of the first applied spring clip 83 tends to force the upper end of said clip back against the inner face of the galley rail 14 so that the upper tongue thereof is automatically maintained out of the way during the build-up process.

75

Now to make a quick check of the overall length and squareness of the build-up type form page, the operator will, by forwardly pressing on the handle 27, draw the carriage-acting frame 20 forwardly against the stop device 52, after which he will rotate the handle 27 approximately 180° in a clockwise direction, thereby extending the push rods 25 and primary rail 24 from their inner extreme positions, shown in Figs. 1 and 2, 10 to their maximum extended positions, shown in Fig. 3, in which latter position they will remain locked against accidental withdrawal. The distance of extension of the primary rail 24 is greater than the distance between the approximately sized type page form and the secondary rail 47, and therefore the secondary rail 47 will be brought into contact with the rear end of the type page form before the primary rail 24 has reached its extreme extended position, with the 15 result that further extension of the rail from this point results in compression of the springs 44, which, acting through the bar 41 and secondary rail 47, will place the type under pressure. It should here be stated, however, that the complete 20 unit, consisting of bars 39 and 41 and elements carried thereby, is laterally shifted so that it is in line with the transverse center of the type page form before this pressure operation is started. For the purpose of this centering of the 25 transversely adjustable pressure and measuring unit, there is provided a center mark 91 on the cover plate 92 of this unit, which cover plate, incidentally, is anchored to the bar 39 by screws 93, overlaps the bar 41 and is provided with a 30 sight opening 94.

The continued forward movement of the primary rail 24 and bar 39 after the secondary rail 47 and bar 41 have come to a stop, against the action of the springs 44, causes an upward movement of the free ends of the pointers 65 over the co-operating scale 63; and if the type page form is of the desired length and squareness, this will be indicated by the position of both pointers over the heavy center scale calibration of the indicator, 45 indicated by zero. If the page be too short but square, the pointers will indicate this position and the extent thereof. If the page be too long but square, this condition and the extent thereof will be indicated by a position of the pointers above the zero line. If either column of type is longer or shorter than the other, this condition will be indicated by the pointer on that side of the instrument. In this way the operator can quickly determine the error in length or squareness, and then, by quick counter-clockwise turn 50 of the handle 27, can release the type unit from pressure and insert or remove shims from between the type to compensate for the error, and then, by another quick turn of the handle, he can get a re-check on the trueness of the form. This process can, of course, be repeated until the desired degree of accuracy can be returned, and such indications of true size and squareness as are read on the indicator are taken under sufficient pressure and under evenly distributed pressure, so that the type page unit will also measure up true when subject to relatively great pressure exerted thereon during the lock-up process.

When the type page unit is finally squared up, 70 the spring clips 83 are applied while the type is still subject to pressure. The front end of the left-hand clip, being already applied at its forward end, is forced into operation position at its rear end by manipulation of the spring-retracted 75 plunger 58, which is pressed inwardly against the

upper end of the left-hand spring clip 83 with sufficient pressure to cause engagement of the upper tongue thereof with the base of the channel in the Monotype slug 84. This done, the right-hand clip 83 is pressed on manually, and with a type held under relatively great pressure, it is not difficult to spring the tongues of the clip over the edges of the slug. The type form page unit can now be released from pressure and transported to the lock-up frame. 10

In the measuring up of the length and trueness of either a single or double column group of type, the indicator is placed in the transverse center of the type unit, but if more than two, three for example, columns of type are to be squared up by 15 means of the instrument, two columns should first be built up and squared up in the manner described, and then the third column should be built up and squared to the previously built-up two columns by moving the indicator mechanism 20 to center between the two previously built-up and last built-up column. The front face of the secondary rail 47 is channelled in the same manner as the galley rail 12 so as to receive the 25 tongues of the spring clips when said spring clips are applied directly to the end type of the group.

What I claim is:

1. In apparatus of the kind described the combination with a galley consisting of a flat rectangular working surface provided at its front 30 and one longitudinal edge with an upstanding flange, of a carriage laterally interlocked to the said longitudinal galley flange and guided thereby for true longitudinal sliding movements over the surface of said galley, means for locking the carriage against longitudinal sliding movements, a member carried by the carriage for extending and retracting movements in respect thereto and longitudinally of the galley, a work-engaging member carried by the said extensible and retractable member in forwardly spaced relation thereto through the medium of a yielding connection, and means for extending and retracting the said extensible and retractable member and retaining the same against accidental displacement from extended and retracted positions. 45

2. The structure defined in claim 1 in which the said work-engaging member presents a transversely straight surface adapted to be brought into engagement with a type form built up therebetween and the front galley flange and in which the said yielding connection between the work-engaging member and the said extensible and retractable member permits further extending movements of the extensible and retractable 50 member longitudinally of the galley after the work-engaging member has come to a stop against one end of a type form and permits pivotal oscillatory movements of the work-engaging member in respect to the said extensible and 55 retractable member. 60

3. In apparatus of the kind described the combination with a galley consisting of a flat rectangular working surface provided at its front 65 and one longitudinal edge with upstanding rail-like flanges, of a carriage laterally interlocked to the longitudinal galley rail and guided thereby for longitudinal sliding movements over the working surface of the galley, means for locking said carriage against longitudinal sliding movement 70 in different adjusted positions, primary and secondary pressure rails extending in substantially parallel spaced relation transversely of the galley, the said primary pressure rail being carried by the said carriage for extending and retracting 75

- movements in respect thereto longitudinally of the galley, and the said secondary pressure rail being carried by the primary rail through the medium of a connection that is yieldable in the 5 direction of the plane of the working surface of the galley, and means for extending and retracting the primary pressure rail and maintaining the same against accidental displacement from its extended or retracted positions.
- 10 4. The structure defined in claim 3 in which the said yieldable connection between the primary and secondary pressure rails is slidably shiftable longitudinally of said primary and secondary rails and transversely of the galley.
- 15 5. The structure defined in claim 3 in which the said yieldable connection between the primary and secondary pressure rails is slidably shiftable longitudinally of said primary and secondary rails and transversely of the galley, and 10 means for indicating the space between the said primary and secondary members at the center point of said yieldable connection therebetween and the angular relation existing between said primary and secondary members.
- 20 6. The structure defined in claim 3 in which said yieldable connection between the primary and secondary pressure rails comprises a crosshead mounted between said primary and secondary pressure rails for sliding movements longitudinally thereof transversely of the galley, said crosshead being split longitudinally of the primary and secondary pressure rails to afford spaced parallel sections, yielding means maintaining the opposite sections of the crosshead under pressure 25 to separate, and means for limiting separating movements of the crosshead sections and affording a pivot point about which said sections are free to oscillate in a plane parallel to the working surface of the galley.
- 30 7. The structure defined in claim 3 in which said yieldable connection between the primary and secondary pressure rails comprises a crosshead mounted between said primary and secondary pressure rails for sliding movements longitudinally thereof transversely of the galley, said crosshead being split longitudinally of the primary and secondary pressure rails to afford spaced parallel sections, yielding means maintaining the opposite sections of the crosshead under 35 pressure to separate, means for limiting separating movements of the crosshead sections and affording a pivot point about which said sections are free to oscillate in a plane parallel to the working surface of the galley, and in further combination with means for indicating the spaced and relative angular positions of said crosshead sections, one with respect to the other.
- 40 8. In apparatus of the kind described the combination with a galley consisting of a flat rectangular working surface provided at its front and one longitudinal edge with upstanding rail-like flanges, of a carriage laterally interlocked to the longitudinal galley rail and guided thereby for longitudinal sliding movements over the working surface of the galley, means for locking said carriage against longitudinal sliding movement in different adjusted positions, primary and secondary pressure rails extending in substantially parallel spaced relation transversely of the galley, the said primary pressure rail being carried by the said carriage for extending and retracting movements in respect thereto longitudinally of the galley, and said primary and secondary pressure rails being connected through the medium of an interposed crosshead that is adjustably 45
- 50 5. The structure defined in claim 3 in which the said crosshead comprising opposed substantially parallel sections, means limiting separating movements of the crosshead sections and permitting limited pivoted oscillatory movements one thereof with respect to the other in a plane parallel to the working surface of the galley, compression spring means normally maintaining the crosshead sections at a point of maximum separation, and a pair of indicating pointers pivoted to a common 55 one of the crosshead sections at spaced points, and links connecting each pointer to the opposite of said crosshead sections.
- 60 9. The structure defined in claim 8 in which the said pointers are arranged in opposed relation and are pivotally anchored to the common crosshead section at points equally spaced from the axis of pivotal oscillation of that crosshead section.
- 65 10. The structure defined in claim 8 in further combination with means for simultaneously extending the said pressure rails and actuating the said carriage-locking means to lock the carriage.
- 70 11. The structure defined in claim 8 in which the said carriage-locking means includes a longitudinally spaced series of apertures in the said longitudinally guided rail of the galley, and co-operating lock pins carried by the said carriage and extendable into and retractable from the said galley rail apertures.
- 75 12. The structure defined in claim 8 in which the said carriage-locking means includes a longitudinally spaced series of apertures in the said longitudinally guided rail of the galley, co-operating lock pins carried by the said carriage and extendable into and retractable from the said galley rail apertures, and in further combination with means for simultaneously extending the said pressure rails and projecting said lock pins into guide rail apertures positioned opposite the same.
- 80 13. The structure defined in claim 8 in which the said carriage-locking means includes a longitudinally spaced series of apertures in the said longitudinally guided rail of the galley, co-operating lock pins carried by the said carriage and extendable into and retractable from the said galley rail apertures, in further combination with means for simultaneously extending the said pressure rails and projecting said lock pins into guide rail apertures positioned opposite the same, and means automatically operative under extending movements of the pressure rails and simultaneous locking of the carriage to take up any clearance which may exist between the carriage and interlocked galley rail.
- 85 14. The structure defined in claim 8 in which the said carriage-locking means includes a longitudinally spaced series of apertures in the said longitudinally guided rail of the galley, co-operating lock pins carried by the said carriage and extendable into and retractable from the said galley rail apertures, in further combination with an adjustable carriage-engaging stop on the longitudinal galley rail.
- 90 15. The structure defined in claim 8 in which the said carriage-locking means including a longitudinally spaced series of apertures in the said longitudinally guided rail of the galley, co-operating lock pins carried by the said carriage and extendable into and retractable from the said galley rail apertures, in further combination with an adjustable carriage-engaging stop on the longitudinal galley rail, said stop comprising a member laterally interlocked to the galley rail and 95

pressed stop pin carried by said member and adapted to interlock with the spaced apertures in said galley.

16. In apparatus of the kind described the combination with a galley consisting of a flat rectangular working surface provided at one longitudinal edge with an upstanding rail-acting flange, of a carriage laterally interlocked to the said longitudinal galley rail and guided thereby for true longitudinal sliding movements over the surface of said galley, means for locking the said carriage against longitudinal sliding movement, a member carried by the carriage for longitudinal extending and retracting movements in respect thereto longitudinally of the galley, said member presenting a straight surface extending transversely over the bottom of the galley at a right angle to the said longitudinal galley rail, and means for extending and retracting said member and retaining the same in its extended or retracted positions against accidental movement, and operating connection between said carriage locking means and said means for extending and retracting the extensible and retractable member 20 for automatically moving the carriage locking means to locked position under extending movements of said means for extending and retracting the extensible and retractable member and automatically unlocking the same under retracting movements of said last named means.

17. In apparatus of the kind described the combination of a flat rectangular working surface, a carriage laterally interlocked to the working surface, carriage adapted to work over said working surface, means for guiding said carriage for true straight line movements in one direction over said working surface and locking the same against angular movements with respect to such a straight line, a member carried by the carriage for extending and retracting movements in respect to the carriage and in the direction of the movement of the carriage, means for extending and retracting said extensible and retractable member, and means for automatically locking the carriage against movement in respect to the working surface under extending movement of said extensible and retractable member and for automatically unlocking said carriage under retracting movement of said extensible and retractable member.

18. In apparatus of the kind described the combination with means providing a flat working surface, of a carriage adapted to be moved in a straight line over the working surface, means for guiding said carriage for true straight line sliding movements over the said working surface, a work engaging member carried by the carriage for longitudinal extending and retracting movements in respect thereto in the plane of the working surface and in the direction of sliding movement of said carriage, operating means for extending and retracting said work-engaging member, and means operatively connected to said operating means for automatically locking said carriage against sliding movement with respect to the working surface as a result of extending movement of said operating means and automatically unlocking said carriage under retracting movement of said operating means.

19. The structure defined in claim 18 in which the said work-engaging member is carried by the carriage through the medium of a yielding connection.

20. In apparatus of the kind described the combination with means affording a flat working

surface, of a carriage, means guiding said carriage for straight line sliding movements over said working surface and locking the same against angular movements in respect to such straight line, means for locking the carriage in an adjusted position against straight line sliding movements, a member carried by the carriage for extending and retracting movements in respect thereto in the line of movement of the carriage, a work-engaging member carried by the extensible and retractable member in forwardly spaced relation thereto through the medium of a yielding connection, and operating means for extending and retracting the said extensible and retractable member.

21. The structure defined in claim 20 in which the said work-engaging member presents a transversely straight surface adapted to be brought into engagement with a type form built up therebetween and the front galley flange and in which the said yielding connection between the work-engaging member and the said extensible and retractable member permits further extending movements of the extensible and retractable member longitudinally of the galley after the work-engaging member has come to a stop against one end of a type form and permits pivotal oscillatory movements of the work-engaging member in respect to the said extensible and retractable member.

22. In apparatus of the kind described the combination with a galley consisting of a flat angular working surface provided at its front portion with an upstanding rail-like flange, of a carriage guided for straight line movements only over the working surface of the galley in a direction transversely of said rail-like flange, means for locking the carriage against accidental sliding movement in different adjusted positions, a pressure rail carried by said carriage in substantially parallel relation to the said rail-like galley flange, means for extending and retracting said pressure rail with respect to the carriage, a work-engaging member spaced from the pressure rail in the direction of the galley flange and adapted to engage work interposed therebetween and the galley flange at laterally spaced points, and a yielding connection between said pressure rail and work-engaging member that is yieldable in the direction of the plane of the working surface of the galley.

23. In apparatus of the kind described the combination with a galley consisting of a flat angular working surface provided at its front portion with an upstanding rail-like flange, of a carriage guided for straight line movements only over the working surface of the galley in a direction transversely of said rail-like flange, means for locking the carriage against accidental sliding movement in different adjusted positions, a pressure rail carried by said carriage in substantially parallel relation to the said rail-like galley flange, means for extending and retracting said pressure rail with respect to the carriage, a work-engaging member spaced from the pressure rail in the direction of the galley flange and adapted to engage work interposed therebetween and the galley flange at laterally spaced points, and a yielding connection between said pressure rail and work-engaging member that is yieldable in the direction of the plane of the working surface of the galley, and means for maintaining the pressure rail against accidental displacement from extended and retracted positions.

24. The structure defined in claim 22 in which the said yieldable connection between the pressure rail and work-engaging member is slidably shiftable with respect to the said pressure rail in a direction transversely of the line of extending and retracting movements of said rail.

25. The structure defined in claim 22 in which the said yieldable connection between the pressure rail and work-engaging member is slidably shiftable with respect to the said pressure rail in a direction transversely of the line of extending and retracting movements of said rail, and means for indicating the space between the said pressure rail and the work-engaging member at the center point of said yieldable connection therebetween and the angular relation existing between said pressure rail and work-engaging member.

26. In apparatus of the kind described the combination with means affording a flat working surface, of a carriage, means guiding said carriage for straight line sliding movements over said working surface and locking the same against angular movements in respect to such straight line, means for locking the carriage in an adjusted position against straight line sliding movements, a member carried by the carriage for extending and retracting movements in respect thereto in the line of movement of the carriage, a work-engaging member carried by the extensible and retractable member in forwardly spaced relation thereto through the medium of a yielding connection, and operating means for extending and retracting the said extensible and retractable member, and indicating means responsive to movement between the work-engaging member and the said carriage carried extensible and retractable member.

27. In apparatus of the kind described the combination with means affording a flat working surface, of a carriage, means guiding said carriage for straight line sliding movements over said working surface and locking the same against angular movements in respect to such straight line, means for locking the carriage in an adjusted position against straight line sliding movements, a member carried by the carriage for extending and retracting movements in respect thereto in the line of movement of the carriage, a work-engaging member carried by the extensible and retractable member in forwardly spaced relation thereto through the medium of a yielding connection, and operating means for extending and retracting the said extensible and retractable member, and indicating means responsive to movement between the work-engaging member and the said carriage carried extensible and retractable member for indicating the space between the work-engaging member and the said carriage carried extensible and retractable member under different stages of compression of said yielding connection.

28. The structure defined in claim 20 in which the said work-engaging member presents a transversely straight surface adapted to be brought into engagement with a type form built up therebetween and the front galley flange and in which the said yielding connection between the work-engaging member and the said extensible and retractable member permits further extending movements of the extensible and retractable member longitudinally of the galley after the work-engaging member has come to a stop against one end of a type form and permits piv-

otal oscillatory movements of the work-engaging member in respect to the said extensible and retractable member, and in further combination with indicating means responsive to movement between the work engaging member and said carriage carried extensible and retractable member for indicating the space and angular relation existing between said last noted members.

29. In apparatus of the kind described the combination with a galley consisting of a flat angular working surface provided at its front portion with an upstanding rail-like flange, of a carriage guided for straight line movements only over the working surface of the galley in a direction transversely of said rail-like flange, means for locking the carriage against accidental sliding movement in different adjusted positions, a pressure rail carried by said carriage in substantially parallel relation to the said rail-like flange, means for extending and retracting said pressure rail with respect to the carriage, a work-engaging member spaced from the pressure rail in the direction of the galley flange and adapted to engage work interposed therebetween and the galley flange at laterally spaced points, a yielding connection between said pressure rail and work-engaging member that is yieldable in the direction of the plane of the working surface of the galley, and indicating means responsive to movement between said work engaging member and pressure rail.

30. In apparatus of the kind described the combination with a galley consisting of a flat angular working surface provided at its front portion with an upstanding rail-like flange, of a carriage guided for straight line movements only over the working surface of the galley in a direction transversely of said rail-like flange, means for locking the carriage against accidental sliding movement in different adjusted positions, a pressure rail carried by said carriage in substantially parallel relation to the said rail-like flange, means for extending and retracting said pressure rail with respect to the carriage, a work-engaging member spaced from the pressure rail in the direction of the galley flange and adapted to engage work interposed therebetween and the galley flange at laterally spaced points, a yielding connection between said pressure rail and work-engaging member that is yieldable in the direction of the plane of the working surface of the galley, and means for maintaining the pressure rail against accidental displacement from extended and retracted positions, and indicating means responsive to movement between said work engaging member and pressure rail.

31. In apparatus of the kind described the combination with a galley consisting of a flat angular working surface provided at its front portion with an upstanding rail-like flange, of a carriage guided for straight line movements only over the working surface of the galley in a direction transversely of said rail-like flange, means for locking the carriage against accidental sliding movement in different adjusted positions, a pressure rail carried by said carriage in substantially parallel relation to the said rail-like flange, means for extending and retracting said pressure rail with respect to the carriage, a work-engaging member spaced from the pressure rail in the direction of the galley flange and adapted to engage work interposed therebetween and the galley flange at laterally spaced points, and a yielding connection between said pressure rail and work-engaging member that is yieldable

in the direction of the plane of the working surface of the galley, and means for maintaining the pressure rail against accidental displacement from extended and retracted positions, and indicating means responsive to movement between said work engaging member and pressure rail,

said yielding connection and indicating means to be adjustably shiftable with respect to the pressure rail in the direction transversely of the line of extending and retracting movement of said rail.

CLARENCE L. SELF.
